UNITED STATES PATENT OFFICE.

RALPH E. NEWTON, OF MILWAUKEE, WISCONSIN.

BASCULE-BRIDGE.

No. 824,135.

Specification of Letters Patent.

Patented June 26, 1906.

Application filed November 5, 1904. Serial No. 231,596.

To all whom it may concern:

Be it known that I, RALPH E. NEWTON, a citizen of the United States, residing at Milwaukee, in the county of Milwaukee and State of Wisconsin, have invented certain new and useful Improvements in Bascule-Bridges; and I do hereby declare the following to be a full, clear, and exact description of the invention, such as will enable others skilled in the art to which it appertains to make and use the same.

This invention is a bridge, and the improvements relate particularly to drawbridges of the vertically-tilting lift or bascule type.

The objects of my invention are, first, to so arrange the joint or hinge by which the tilting draw-span is connected to the fixed approach of the bridge that the live or moving loads produced by traffic over the draw-span will be supported independently of the pivot-shaft, thereby permitting the shaft and bearings to be made much lighter and at less expense than in bridges where the duty of the shaft is not only to support the weight of the bascule while tilting, but also to support the weight of traffic over the bridge; second, to make as short as possible the cantaliver or overhanging span of the bascule, being that portion of the bascule which projects over the channel as a cantaliver; third, to utilize the dead-weight of the approach-span in resisting the upward reaction caused by the inner engaging end of the bascule; fourth, to utilize the leverage of the approach-span in resisting the upward reaction caused by the inner engaging end of the bascule.

An additional advantage attained by my improved construction is that the vertical pressure due to the combined weight of the bascule and approach-span upon the outer abutments or supporting-piers is received upon the central plane of said abutments or piers.

In the drawings, Figure 1 is a longitudinal section of the bridge, showing one bascule with its approach-span. Fig. 2 is a modified form, showing the supporting-pier arranged under the pivot-line of the bascule.

It is evident that the bridge may consist of either one bascule, as shown in the drawings, or two bascules arranged so that their projecting ends meet over the channel, depending upon the width of the channel.

In my improved construction the stationary portion of the structure, known as the "approach" A, is made to extend out to the

edge of the channel and is cut away, as shown, to receive the rear end of the bascule, a portion of the approach extending some distance in advance of the pier. To this stationary portion, at or near its outer end, is fastened a cross girder, beam, or truss B, extending approximately parallel to the channel or approximately at right angles to the direction of the crossing formed by the bridge and slightly above the level of the cut-away portion to form a projection or rest. The bascule C is supported by means of its fixed pivot-shaft or trunnion P upon the approach-span. At the rear of pivot P and secured to the approach-span A is a similar cross girder, beam, or truss D, the bottom of which engages the rearwardly-projecting end or nose C' of the bascule, which is adapted to take under and rest against the abutment, beam, or girder D.

The bascule when in its horizontal position rests upon the support B in front of the pivot P, and its rear end C' engages under the support D, the supports B and D thereby taking the reactions caused by both the weight of the bascule and the weight of the live load due to traffic over the bridge. It will be seen that the pivot P is thus relieved of strain while the span is closed and is only brought into use when the bascule is in a position other than horizontal, then being subjected only to the weight of the bascule itself.

An important feature of the improvements in this construction is that the support B, being located far out on the approach A, preferably at the very edge of the channel, gives firm support to the bascule at a point as far as possible out toward the overhanging or cantaliver portion of the bascule, thereby reducing the overhanging length of the cantaliver and permitting the bascule to be made of much lighter material than would be possible if the weight were carried by the pivot P farther back upon the approach-span.

Another desirable feature of this construction is the adaptability of the dead-weight and the leverage of the approach-span to resist the upward reaction of the inner engaging end of the bascule.

It will be noted that by this construction it is possible to support the bascule at a point on the approach A beyond the vertical center line of the pier and at the same time accomplish the result that the reaction on the pier will be always purely vertical, no overturning movement acting upon it.

By the means above described the trunnion or trunnion-shaft is called upon to support only the dead-weight of the bascule and its counterweights, enabling the trunnion 5 axle and bearings to be reduced to the smallest possible dimensions and cost, the bearings in which the trunnions are received being of larger diameter than the trunnions, and by supporting the live weight, being the 10 load due to traffic, upon the extreme end of the approach-span, as by the girder B, the actual cantaliver span of the bascule is reduced to the minimum, and consequently the dead-weight of the bascule and its cost 15 are minimized, further resulting in minimizing the reaction of the weight of the bascule on the approach-span, thereby permitting its weight and cost likewise to be reduced.

What I claim as my invention, and desire 20 to secure by Letters Patent, is—

1. A bascule-bridge comprising a substantially horizontal approach-span, a bascule or tilting arm or span pivotally mounted directly on the approach-span near the outer 25 end thereof, a support carried by said approach-span and located outside of or beyond the pivots to engage said bascule, and a stop carried by said approach-span on that side of the pivotal point of the bascule opposite 30 said support, the stop adapted to engage the inner or counterweighted end of said bascule.
2. A bascule-bridge comprising an approach-span, the span comprising longitudinal girders, a bascule-leaf permanently pivoted on the approach-span and between the 35 girders near the outer ends thereof, cross-girders extending between the longitudinal girders on opposite sides of the pivotal point of the bascule, the forward girder supporting 40 the downward stress of the bascule, a rearward extension of the bascule adapted to take under the rear girder when the bascule is in its lowered position to relieve the pivotal point of the bascule of downward stress, the 45 girders operating to entirely relieve the pivotal point of the bascule of strain, save from dead-weight.
3. A bascule-bridge comprising an approach-span, a bascule-leaf pivotally secured

near one end of the approach-span, supports 5 carried by the approach-span and located in front of and behind the pivotal point of the bascule, the bascule adapted to bear against the supports when in lowered position to relieve the pivotal point of stress, the pivotal 55 point of the bascule and the supports being localized near the forward end of the approach-span, and a pier for supporting the approach-span, said pier adapted to be located independently of the clustered supports. 60

4. A bridge comprising an approach-span, a bascule, one end of which is pivoted adjacent the forward end of the span, a stop carried by the span in rear of the pivotal point 65 of the bascule, a second stop carried by the span in front of the pivotal point of the bascule, the bascule when in lowered position adapted to engage both stops whereby the upward and downward stresses are removed 70 from the pivotal point of the bascule, and means for supporting the span.

5. In a bridge, the combination with a span having a cut-away portion, of a bascule the rear end of which is fixedly pivoted in 75 said cut-away portion, an approximately horizontal abutment carried by the span and projecting over its cut-away portion and a rearwardly-extending nose carried by the bascule and adapted to take under the abutment to relieve the pivotal support of the bascule of strain. 80

6. A bridge comprising a span, piers supporting the same, the span projecting in advance of the piers and being cut away at its 85 forward end, a bascule, the rear end of which is received in the space formed by the cut-away portion of the span, a fixed pivot passing through the bascule and means for supporting the bascule on both sides of its pivotal point and in advance of the piers to relieve the pivot of strain. 90

In testimony whereof I affix my signature in presence of two witnesses.

RALPH E. NEWTON.
